Patented Oct. 24, 1916.

UNITED STATES PATENT OFFICE.

THOMAS HOWARD, OF OWENSBORO, KENTUCKY, ASSIGNOR OF ONE-HALF TO WILLIAM E. WILLIAMS, OF OWENSBORO, KENTUCKY.

TOY.

1,202,721.

Specification of Letters Patent.

Patented Oct. 24, 1916.

Application filed March 1, 1916. Serial No. 81,435.

To all whom it may concern:

Be it known that I, THOMAS HOWARD, a citizen of the United States, residing at Owensboro, in the county of Daviess, State 5 of Kentucky, have invented a new and useful Toy; and I do hereby declare the following to be a full, clear, and exact description of the invention, such as will enable others skilled in the art to which it appertains to 10 make and use the same.

This invention relates to the art of games and toys, and more especially to an improved toy, comprising one or more inclined tracks so that a series of balls will roll from one 15 track to the other, one of said tracks being tiltable, whereby every odd ball or marble may be automatically returned to the uppermost track, the movements of the balls or marbles being continuous, until substantially 20 all the balls or marbles reach a depository hopper or compartment at the base of the apparatus, thereby creating amusement for children.

Another object of the invention is the 25 provision of a toy of this kind, in which simple, efficient, desirable and practical features of construction are involved.

Another object of the invention is the provision of a device of this kind, which may be 30 easily and cheaply constructed, more especially of any suitable material, wood, metal or the like, and sold at a reasonable cost.

In practical fields the details of construction may necessitate alterations, falling within 35 in the scope of what is claimed.

The invention comprises further features and combination of parts, as hereinafter set forth, shown in the drawings and claimed.

In the drawings: Figure 1 is a view in side 40 elevation of the improved toy constructed in accordance with the invention, and illustrating one of said tracks tilted in dotted lines. Fig. 2 is a vertical sectional view. Fig. 3 is a sectional view on line 3—3 of Fig. 1; Fig. 4 is a sectional view on line 4—4 of Fig. 1. Fig. 5 is a top plan view of the uppermost inclined track showing the adjacent faces of the sides of said track provided with convolutions arranged in staggered relation, 45 whereby as each ball gravitates down the track, the motion is substantially an intermittent or zig-zag movement. In other words, the ball or marble is substantially crossed first to one side and then the other, 50 thereby retarding its speed.

Referring more especially to the drawings, 1 designates the base, and secured to the upper face thereof near one end by means of a screw or sprig 2 is a cleat 3, to the opposite ends of which the standards 4 are secured by 50 the screw or sprig 5. These standards 4 rise vertically from the base, and are in parallelism. Also secured to the upper face of the base adjacent the opposite end thereof by means of the screws or sprigs 6 are the 65 cleats 7, 8 and 9, arranged to constitute a flange, of rectangular outline in plan view, thereby providing a depository space or hopper 10 for a series of balls or marbles or the like. The bottom of this space 10 is provided with a plurality of semi-spherical depressions, which may or may not be provided with characters of denomination, such as 1 to 10 inclusive, or the like, so that whoever may be lucky enough to have the majority 70 of balls or marbles to engage a greatest number of depressions of the highest denomination wins. However, the numerals of denomination may be eliminated if so desired, or if used may be varied. Rising from the 75 inner ends of the cleats 7 are standards 11, which are in parallelism. Also secured to the base 1 in any suitable manner and having one end between the lower ends of the cleats 11 is a short block 12, which has its upper 80 face inclined and provided with a groove 13 constituting an inclined track. The standards 4 are of greater height than the standards 11, and secured by screws or sprigs 14 to and between the upper end portions or 85 extremities of both sets of standards 4 and 11 is an inclined groove track 15. The inner adjacent faces of the flanges or sides for substantially half their length toward the lowermost part of the inclined track 15 are provided with convolutions 16 disposed in 90 staggered relations, in order to impart substantially an intermittent and ziz-zag movement to the ball or marble as it travels the inclined track in order to retard its movement. A second inclined track 17 is secured by screws or the like 18 to and between the standards 4 and 11, and below the inclined track 15, at an acute angle thereto, so that as 95 each ball or marble reaches the lowermost end of the track 15, it will fall upon the track 17. One end of the track 17 has an abutment member 19, to prevent the ball or marble from passing off the rear end of said track 17. 100

110

Pivots mounted upon a pin 20 between the standards 4, said pin 20 being immediately under the end portion 21 of the track 17, is a track 22, which is so pivoted as to afford long and short ends 23 and 24. The under face of the short end portion is provided with a weight 25, of sufficient capacity, as to hold the track 22 upon a less inclination than the track 17 and at an acute angle to the track 17, but in parallelism with the track 15 substantially, whereby the end portion 23 of the track is held normally in contact with the abutments or stops 26 upon the inner faces of the standards 11. However, the member 25 is of such weight that when a ball or marble reaches the end portion 23, the weight of the marble or ball is sufficient to overcome or overbalance the weight of the member 25, thereby tilt the track 22 to the position shown in dotted lines in Fig. 1. However, in practice each of the balls or marbles is of such weight compared to the weight of the member 25, as to not overbalance the weight 25, until the ball practically reaches the flange 27 at the extremity of the end portion 23, whereupon the marble or ball will tilt the track 22 to the inclined dotted line position in Fig. 1.

30 The face of the groove of the end portion 24 of the track 22 near the extremity of the end portion 24 is provided with a depression or pocket 29, adjacent to which an abutment 30 is fixed, to prevent the ball or marble from rolling off the end of the part 24.

Pivoted upon a pin 31 in a slot 32, and substantially midway the ends of the track 15 is a trip lever or dog 33, the grooved nose 34 of which is designed to assume a position in the path of the series of balls or marbles 34, while the tail 35 is in the path of the balls or marbles, when they reach the track 17.

45 In operation the balls or marbles are first deposited in the track 15 so as to be held by the nose of the trip dog. The tail end of the trip dog is then tilted manually, so that the nose of the trip dog is moved from the path 50 of the foremost ball or marble, which gravitates in a zig-zag manner along the opposite grooved faces of the track 15, such convolutions or grooves acting to retard the ball or marble to a degree to enable tilting lever 55 23 to operate and return to its normal position ready to receive the next ball or marble. The first ball or marble then falls upon the track 17 until it contacts with the tail end of the trip dog, which causes the nose to be 60 moved to release the next ball. However, the first ball passes from the track 17 to the end portion 24 of the track 22 and into the pocket or depression 29. The second ball or marble after having left the track 15 and 65 is passing along the track 17 engages the tail

end 35 and releases the third ball. The second ball or marble passes on to the end portion 24 of the track 22, and owing to the first ball resting in the depression 29, the second ball travels downwardly upon the track 22, until it reaches the extremity of the end portion 47 of the track 22, whereupon its weight overbalances the combined weight of the first ball and the weight 25, thereby tilting the track 22 in a dotted line position shown in Fig. 1, so that the upper edges of the sides of the end portion 24 of the track 22 will contact with the beveled parts 37 of the track 15, whereas the extremity of the end portion 23 is in a position to cause the second ball to pass into the track groove 13 and thence into the depository space 10. When the track 22 is in the position shown in dotted lines in Fig. 1, the first ball, owing to the inclined portion 38 of the depression 29 leaves the depression and is returned to the track 15. These operations are continued, until all the balls or marbles excepting the last ball which remains in contact with the nose of the trip dog, reach the depository space 10.

Uprights 4 and 11 may be made removable from the base, to make the toy more compact for shipment.

The invention having been set forth, what is claimed as new and useful is:—

1. In a toy for children, a frame comprising a base, a pair of inclined tracks secured to the upper part of the frame, one above the other and at an acute angle to each other, a third track pivoted in the frame at the lowermost extremity of the lowermost of the first mentioned tracks, so that a ball rolling down the pivoted track will act as means to overbalance the combined weight of another ball and a weight at one end of the pivoted track, for returning another ball to the uppermost of the first mentioned tracks, a weight carried by one end of the pivoted track, and a trip dog pivoted in the uppermost of the first mentioned tracks to be tripped by a ball, for releasing one ball at a time of a series of balls in the uppermost of the first mentioned tracks.

2. In a toy for children, a frame comprising a base, a pair of inclined tracks secured to the upper part of the frame, one above the other and at an acute angle to each other, a third track pivoted in the frame at the lowermost extremity of the lowermost of the first mentioned tracks, so that a ball rolling down the pivoted track will act as means to overbalance the combined weight of another ball and a weight at one end of the pivoted track, for returning another ball to the uppermost of the first mentioned tracks, a weight carried by one end of the pivoted track, and a trip dog pivoted in the uppermost of the first mentioned tracks to be tripped by a ball, for releasing one ball at 125

a time of a series of balls in the uppermost of the first mentioned tracks, the uppermost track of said pair of tracks having means to partially retard each ball, when released, as it rolls down the uppermost track.

3. In a toy for children, a frame comprising a base, a pair of inclined tracks secured to the upper part of the frame, one above the other and at an acute angle to each other, a third track pivoted in the frame at the lowermost extremity of the lowermost of the first mentioned tracks, so that a ball rolling down the pivoted track will act as means to overbalance the combined weight of another ball and a weight at one end of the pivoted track, for returning another ball to the uppermost of the first mentioned tracks, a weight carried by one end of the pivoted track, and a trip dog pivoted in the upper-

most of the first mentioned tracks to be tripped by a ball, for releasing one ball at a time of a series of balls in the uppermost of the first mentioned tracks, the uppermost track of said pair of tracks having means to partially retard each ball, when released, as it rolls down the uppermost track, and a depository space at the base of the frame at one end, in which the balls are delivered, one at a time, from the tilttable track when tilted.

In testimony whereof I have signed my name to this specification in the presence of two subscribing witnesses.

THOMAS HOWARD.
